GAS GENERATOR

Edward P. Gillette, Toledo, Ohio, assignor to Gillette Research Corporation, Toledo, Ohio, a corporation of Ohio

Application May 17, 1934, Serial No. 726,097

2 Claims. (Cl. 263—3½)

This invention relates to gas generators, but more particularly to apparatus for burning material and recovering the gas dissociated therefrom during the burning operation.

5 An object is to produce a new and improved gas generator which is capable of burning sizable quantities of material, such as limestone, and recovering the gas dissociated therefrom in a continuous, economical and practical manner.

10 Other objects and advantages will hereinafter appear, and, for purposes of illustration but not of limitation, an embodiment of the invention is shown on the accompanying drawings, in which:

15 Figure 1 is a transverse sectional elevation of the gas generator or kiln taken on the line 1—1 of Figure 3 showing the relative arrangement of the furnaces with respect to the vertical retorts;

Figure 2 is a transverse section on the line 2—2 of Figure 3;

20 Figure 3 is a vertical sectional elevation of the generator taken substantially on the line 3—3 of Figure 1;

Figure 4 is an enlarged side elevation of a 25 lower portion of one of the tubes showing the material discharge apparatus and the associated parts; and

Figure 5 is an enlarged vertical sectional view 30 of one of the pocketed discharge rotors and its housing together with the adjacent vertical tube.

35 The illustrated embodiment of the invention comprises a gas generator in the form of a kiln for burning material, such as limestone, or other carbon dioxide containing material, dissociating the gas from the material as the latter moves in a stream through vertical tubes by heat applied indirectly through the walls of the retort. As shown, the lower portion of the generator is supported by a structural steel frame 10 consisting of a plurality of uprights and bracing bars and having a platform 10a, and mounted on the platform is a plurality of vertical retorts or tubes 11, which are elongate in cross-section, as indicated in Figure 1, and, in this instance four tubes are arranged in spider-like formation radiating from an upright post or column 12 of suitable refractory material, which provides an anchor or support for securing the inner edge portions of the tubes 11. The outer edge portions of the retorts 11 are embedded or secured in walls 13 of suitable refractory material.

40 As shown in Figure 1, the walls 13 adjacent each pair of tubes extend outwardly to provide a chamber 14, and outer wall 15 being closed except for an opening 16 to receive the nozzle of

an oil or gas burner for forcing heat toward the inside of the chamber 14 for heating the adjacent vertical walls of the retorts 11. It will be apparent that coal or other fuel may be employed, if desired. In this manner it is apparent that four 5 furnaces are sufficient adequately to heat the several side walls of the retorts 11. The top wall of each furnace chamber 14 is closed by a wall 17, which inclines upwardly and inwardly, as indicated on Figure 3, the bottom of each furnace 10 being closed by a wall 18, which is supported by a wall 19 from the platform 10a.

As indicated in Figure 3, the top walls 17 of the furnaces merge into an annular vertical wall 19 in which is embedded and anchored the outer 15 edge portions of the tubes or retorts 11. It is thus apparent that the retorts 11 are properly secured in position at the inner and outer edge portions, leaving the intermediate portions thereof exposed to the heat generated in the furnace 20 chambers 14. The heated gases and products of combustion from the furnaces pass upwardly through flues or passages 20 between the side walls of the retorts, it being understood that the upper ends of these passages are open to the outside. In order securely to hold the annular 25 upright wall 19 in position, metal hangers 21, spaced by I-beams 22, are provided for this purpose.

The inside of the annular wall 19 adjacent the upper end thereof inclines inwardly, as indicated 30 at 23, in order to secure the full benefit of the heat from the gases passing upwardly through the flues 20. As shown in Figure 3, the wall 19 extends upwardly above the inclined surface 23, and mounted on the upper end of this wall is a hopper 35 24 to receive material, such as limestone, which flows continuously by gravity into the several retorts 11. It will be understood that the material will be directed from the hopper 24 to the retorts 11 by suitable chutes or funnels 24a 40 through which extend pipes 24b for smoke and gases from the flues.

The retorts 11 are made up of a plurality of blocks or tiles preferably of silicon carbide, which are secured together by a suitable cement to provide air and gas-tight joints between several 45 blocks.

It will be observed that adjacent the outer edge portion of each of the tiles are louvers 25, which incline downwardly and inwardly, as indicated in 50 Figure 3, to allow the material to pass downwardly thereover, the space 26 between the louvers providing openings through which gas, such as carbon dioxide dissociated from limestone, may freely pass into a chamber 27 on the outer edge 55

portion thereof. The gas is drawn off from the lower end of the gas collecting chamber 27 through a pipe 28, which may lead to any suitable receptacle. If desired, a suction pump (not shown) may be utilized to accelerate the flow of gas from the gas collecting chamber 27.

It will be seen in Figure 3 that the retorts 11 extend below the furnaces 14 and terminate at the platform 10^a. Secured to the platform 10^a and 10 registering with the opening at the lower end of each retort 11 is a tube 29 through which the material is adapted to flow. The tube 29 extends downwardly below the tube 28 and has a downwardly and laterally inclined bottom wall 30 to 15 divert the flow of material laterally to a discharge apparatus housing 31 in which is disposed a rotary discharge wheel 32. Covering the upper portion of the wheel 32 and forming a part of the housing 31 is a laterally extending portion 33, 20 which extends at substantially right angles from the tube 29 slightly above the lower end. Connected to the outer end of the portion 33 is a downwardly curved apron 34 which snugly fits with a few thousandths of an inch clearance the 25 upper portion of the wheel 32, an internal shoulder 35 being provided between these portions which is rearwardly inclined, as indicated in Figure 5. It will also be noted that the bottom wall 36 of the housing 31 is shaped snugly to embrace 30 the lower portion of the discharge wheel 32, leaving a very slight clearance with the wheel.

Formed in the wheel or rotor 32 is a plurality of pockets 37 which extend horizontally across the face of the rotor, in this instance three pockets 35 being provided. The pockets 37 are relatively deep with the sides thereof tapering slightly and with the mouth 38 of each pocket facing in a direction opposite to the direction of rotation of the rotor 32 and the bottom 39 thereof inclined upwardly when the pocket is disposed in material-receiving position. The purpose of this arrangement is to enable each pocket to be partially filled when in receiving position, such as the pocket A in Figure 5. As the rotor turns in a clockwise 40 direction (Figure 5), some of the material in the pocket drops therefrom so that when the pocket is in position to pass the shoulder 35 with the pocket moving toward a vertically disposed position the material can drop into the bottom portion of the pocket, leaving the mouth free of material, as indicated in the pocket B of Figure 5.

This is found to be of outstanding importance in that it militates against material wedging between the rotor and housing and interfering with 55 the free turning movement thereof and enabling the use of a less powerful motor to drive the rotor. By obviating the shearing action of the material between the housing and rotor, it makes possible the use of much lighter material and greatly reduces the wear of the parts. It will be apparent that a rotor of this character is not only of importance in enabling the use of a relatively simple motor to operate, but, in addition, an effective seal is provided by the material to prevent to a large extent the ingress of air into the retorts. It is obvious that the admission of air to the retorts is objectionable in that it would prevent the obtaining of gas of the desired purity.

Each rotor is mounted on a shaft 40 on which an arm 41 is free to oscillate. The arm 41 is connected by a rod 42 to an eccentric 43, which is driven by a motor 44 to impart rocking movements to the arm 41. On the arm 41 is pawl 45, which recurrently meshes with teeth 46 on a ratchet wheel fixed for rotation with the rotor 32. In this manner it is apparent that turning movement is imparted positively to the rotors 32 at a relatively slow speed accurately controlled 10 by an adjustable sleeve 47, which controls the number of teeth engaged by the pawl 45.

Although the embodiment of the invention which is herein shown and described, is concerned with the burning or heating of limestone 15 and the dissociation of carbon dioxide, the invention is not limited thereto because the generator can be used to advantage in treating other material and recovering other gases which are given off. Furthermore, the apparatus can be used for 20 heating or drying materials where it is disadvantageous to have them contact directly with the furnace flame and fuel gases. For example, limestone can be calcined and the calcium oxide recovered without collecting the gas, if desired, and this would be desirable as compared with many methods for burning comminuted or granular limestone which cannot be readily burned in the ordinary vertical kiln in view of objectionable caking or fusing at high temperatures 25 tending to clog and shut off the draft.

It is to be understood that numerous changes in details of construction, arrangement and operation may be effected without departing from the spirit of the invention, especially as defined 30 in the appended claims.

What I claim as new and desire to secure by Letters Patent is:

1. A gas generator comprising a vertically disposed support, a plurality of tubes fixed at their inner edge portions to said support and arranged radially thereof, means to introduce material to the upper ends of said tubes, means providing gas chambers disposed laterally of the material stream through said tubes for receiving gas dissociated from the material during its passage through the tubes, means to discharge material from the lower ends of said tubes, a furnace between each pair of adjacent tubes for heating the walls thereof, and a casing common to the several tubes and providing flues for the products of combustion of said furnaces. 40 45 50

2. A gas generator comprising a vertically disposed column, a plurality of upright tubes arranged in equidistantly spaced relation, said tubes being elongate in cross section and having one narrow side of each tube fixed to said column, means providing a gas passageway along the opposite narrow sides of each tube, openings from the tube into the passageway, an enlarged furnace housing between each adjacent pair of tubes extending laterally from the lower portion thereof to enable heat to be transmitted from one housing to one wall of each of the adjacent tubes, and a casing above said furnace housings common to the several tubes and providing flues for the products of combustion. 55 60 65

EDWARD P. GILLETTE.
